UNITED STATES PATENT OFFICE.

DANA H. BENJAMIN, OF CLEVELAND, OHIO, ASSIGNOR TO SOLOMON D. GUGGENHEIM,
OF CLEVELAND, OHIO.

GEARING FOR WASHING-MACHINES.

1,265,289.

Specification of Letters Patent.

Patented May 7, 1918.

Application filed May 27, 1915. Serial No. 30,825.

To all whom it may concern:

Be it known that I, DANA H. BENJAMIN, a citizen of the United States, residing at Cleveland, in the county of Cuyahoga and 5 State of Ohio, have invented certain new and useful Improvements in Gearing for Washing-Machines, of which the following is a specification.

This invention relates generally to mechanical movements, and particularly to that class of such devices utilized for operating washing machines. More specifically the invention relates to a mechanical movement used for washing machines and it comprises a supporting frame, a driven member, and driving mechanism for the driven member including two oppositely driven wheels having frictional engagement with the receptacle driven member, and suitable means 15 for rotating said wheels and for moving them successively into and out of engagement with the receptacle driven member.

The invention may be further briefly summarized as consisting in the construction 25 and combination of parts hereinafter set forth in the following description, drawings and claims.

Referring to the drawings, Figure 1 is a side elevation of the device applied with 30 parts broken away; Fig. 1^a is a detail section of the wedge adjustment for the cam; Fig. 2 is an end view with one gear case in section; Fig. 3 is a sectional view taken on the line corresponding to a vertical plane 35 cutting the axis of the driven member and back of the oppositely driven friction wheels; Fig. 4 is a horizontal section taken on a line cutting the axis of the driven member; and Fig. 5 is a vertical sectional view 40 of the driving mechanism; Fig. 6 is a top plan view of the trough and cylinder; and Fig. 7 is a cross section of these parts.

In carrying out the invention any preferred form and construction of parts may 45 be employed so long as it possesses the necessary characteristics, but I have shown one arrangement which is effective, and in such embodiment 1 represents a suitable framework provided with a trough-shaped receptacle 2 having suitable heads 3 and 4, the former being provided with a bearing consisting of a flanged sleeve 5 extending through the head and having threaded to the inner end a flange 6 adapted to be secured to the inner face of the head. The

opposite head 4 is provided with a bushing 7 adapted to receive a pin 8 arranged in the bushing and having a reduced trunnion portion 9. This pin 8 is held in place by a lock pin 10 passing through projecting portion 60 of the sleeve 7 and through the pin 8.

Mounted in the bearing sleeve 5 is an agitator driven shaft or member 11 having on the outside of the head 3 a main driving member 12 provided at its periphery with 65 a flange 13. This flange is provided internally with an annular V-shaped groove 14 for a purpose to be described. This driven member is also provided with a suitable pilot or shaft extension 15, as shown in Fig. 70

4. The inner end of the driven shaft 11 is provided with a squared portion 16 entering a correspondingly shaped opening in the socket member 17 secured in the head 18 of a cylindrical agitator 19, the other head 20 75 of this agitator being provided with a suitable bearing member 21 adapted to receive the trunnion portion 9 of the pin 8. The cylindrical agitator 19 has suitable openings 22 through the wall and an enlarged opening 23 extending the length of the cylinder and adapted to be closed by a door or plate 24 having cleats 25 on the bottom thereof. These cleats have extensions 26 extending 80 under the wall at one edge. About the opposite edge a suitable latch 27 is provided on the outside wall of the cylinder to hold the door in place at this point. The inner wall of the cylinder is also provided with longitudinally disposed baffle plates 27' spaced 90 around the inner wall.

The mechanism for driving the driven shaft or member is mounted in a casing 28 having diametrically disposed bearings 29 and 30 which receive a diagonally disposed 95 operating shaft 31 which is further mounted in bearings 32 and 33 secured to the head 3. This shaft has on its lower end a gear 34 driven by a pinion 35 operated by a motor. The upper end of the shaft is provided with 100 a bevel pinion 36 meshing with a gear 37 secured to a vertically disposed shaft 38, shown in dotted lines in Fig. 1, and having upon the upper end a bevel pinion 39, engaging a bevel gear 40 mounted upon a shaft 105 supported in a bearing 41 and having on the opposite side of this bearing a clutch member 42. This clutch member is adapted to be engaged by a wringer clutch member 43 slidably mounted upon a wringer shaft 110

44. This shaft is provided with a wringer roll 45 engaging with another wringer roll 46, both of which are supported in a suitable framework 47.

5 The driving mechanism will now be described. Forming part of the front of the casing 28 is a bearing 48 having mounted therein a shaft 49 extending into the casing 28 and to a point within the flange 13 of the 10 driven shaft or member 12. This shaft has loosely splined to it, just inside of the front of the case, a clutch member 51 having a groove adapted to receive the ends of a forked shifting lever 52 pivoted to a suitable 15 bracket 53 forming a part of the case. The handle 54 of this lever projects up through a suitable opening in the casing. This clutch member co-operates with a clutch member 55 integral with a worm gear 56 loosely 20 mounted upon the shaft 49. This worm gear meshes with a worm 57 secured to the shaft 31. Secured to the shaft 49, just inside of the worm gear 56, is a main driving gear 58 for a purpose to be described. 25 The shaft 49 is continued loosely through a swinging frame 59 and through the end of a link 60 which has a bearing portion 61 at its lower end adapted to engage the pilot shaft portion 15 of the driven 30 shaft or member. In this way the shaft 49 is supported at both ends with respect to the axis of the driven shaft or member. The swinging or pivoted frame 59 is provided with a bearing 62 for a direct drive friction 35 wheel shaft 63, a bearing 64 for a reverse friction wheel drive shaft 65, and a back gear shaft supporting boss 66 carrying a back gear shaft 67. This frame is also provided with an outwardly extending bracket 40 68 shown in Fig. 1 and having on the outer end a pair of bearing boxes 69 which support a worm shaft 70 upon which is mounted a worm wheel 71 adapted to be driven by mechanism to be described. The outer end 45 of the shaft 70 is provided with a cam 72 adapted for engagement with a suitable stop preferably comprising a wedge 73 mounted in a bracket 74 secured to the head 3. This wedge is held in any adjusted position by 50 means of adjusting screws 75. Secured to the shaft 63 on the inside of the frame and within the flange 13 is a friction wheel 76 having a periphery wedge-shaped in cross section for engagement with the V-shaped 55 groove 14. On the outside of the frame this same shaft is provided with a spur gear 77 meshing with the main driving gear 58 and beyond this same shaft is provided with a worm 78 meshing with the worm wheel 71. 60 The shaft 65 is provided with a spur gear 79 meshing with a back gear 80 mounted upon the back gear shaft 67. This back gear 80 in turn meshes with the main driving gear 58. On the inside of the swinging 65 or pivoted frame 59 this shaft 65 is provided

with a friction wheel 81 similar in all respects to the friction wheel 76 except that it has the opposite direction of rotation. In order to cause the cam 72 to normally remain in engagement with the wedge 73 a 70 spring 82 is arranged between an ear 83 on the bracket 68 and a fixed bracket 84 secured to the main frame. In this way the entire swinging frame has a tendency to swing in a clockwise direction on its center, thus 75 maintaining the engagement between the cam and the wedge.

In operation the door of the cylinder is opened and the articles to be washed are inserted and the door closed, suitable washing solution having been previously placed in the trough or tub. The clutch member 51 is thrown in the proper direction to cause the driving of the main driving gear 58 with the result that the two friction 80 wheels 76 and 81 are driven, and in like manner the cam 72 is driven, causing the swinging frame to bring one or the other of the friction wheels into engagement with the driven shaft or member of the receptacle. 85 This causes the receptacle cylinder to be oscillated, with the result that the articles within are cleansed by the action of the baffles 27.

Having described my invention, I claim:— 95

1. A mechanical movement, comprising a driven member, oppositely rotatable driving members adapted to co-operate with the driven members by frictional engagement therewith, means operated in synchronism 100 with the driving members for shifting said driving members alternately into engagement with the driven member, and means for driving said driving members.

2. A mechanical movement, comprising a 105 driven member, a movable supporting frame, oppositely rotatable driving members supported on said frame and adapted at the proper time to have frictional engagement with the driven member, means for driving 110 said oppositely rotatable driving members, means operated in synchronism with the driving members for shifting said frame to bring the oppositely rotatable driving members alternately into engagement with 115 the driven member, and means for operating the several parts.

3. A mechanical movement, comprising a casing, a driven wheel mounted therein, a frame pivotally secured to the casing, a pair 120 of oppositely rotatable friction driving wheels carried by said frame and adapted to engage the driven wheel at the proper time, means for driving the friction wheels, and means operated in synchronism with 125 the friction wheels for shifting said frame to bring said friction wheels alternately into operative engagement with the driven wheel.

4. In a mechanical movement, a casing, a 130

friction wheel mounted therein, a frame pivotally secured to the casing, a pair of oppositely driven friction wheels carried by said frame and adapted to engage the friction wheel at the proper time, means for driving the friction wheels, and means for shifting said frame to bring the oppositely driven friction wheels successively into operative engagement with the friction wheel, and comprising a cam, a stop, one being fixed relative to the other and one mounted upon the pivoted frame, and means for driving said cam.

5. In a mechanical movement, a casing, a friction wheel mounted in said frame, a frame pivotally secured to the casing, a pair of oppositely driven friction wheels carried by said frame and adapted to engage the friction wheel at the proper time, and means 5 for shifting said frame to bring the oppositely driven friction wheels successively into operative engagement with the friction wheel and comprising a cam, a stop, one being fixed relative to the other and one 5 mounted upon the pivoted frame, and means operated from the friction driven wheel mechanism for operating said cam.

6. In a mechanical movement, a casing, a friction wheel mounted in the same, a frame 0 pivotally secured to the casing, a pair of oppositely driven friction wheels carried by said frame and adapted to engage the friction wheel at the proper time, and means 5 for shifting said frame to bring the oppositely driven friction wheels successively into operating engagement with the friction wheel and comprising a cam mounted on said frame, suitable gearing for said cam and operatively connected to a driven part 0 carried by the casing, and a stop mounted on the main frame and adapted to be engaged by said cam.

7. In a mechanical movement, a casing, a driven member having an internal annular 5 friction groove, a pivoted frame supported on the casing, a pair of friction wheels carried by said pivoted frame and adapted for engagement in the friction groove of the driven member at the proper time, means 0 for driving the friction wheels carried by the pivoted frame in opposite directions, and means for automatically shifting the pivoted frame to bring the friction wheels successively into engagement with the driven 5 member.

8. In a mechanical movement, a driven member, a pair of oppositely driven wheels for coöperation with the driven member, said parts having coöperating friction surfaces, one being a V-shaped groove and the other a V-shaped ridge, a movable frame carrying the oppositely driven wheels, means for driving the oppositely driven wheels, and means for shifting the movable frame.

9. In a mechanical movement, a casing, a 60 driven member having an internal V-shaped recess, a movable frame supported on the casing, oppositely driven friction wheels having V-shaped peripheries conforming to the V-shaped recess in the driven member, 65 means for driving said oppositely driven friction wheels, and means for moving said frame.

10. In a mechanical movement, casing, a driven member having an internal V-shaped 75 recess, a movable frame supported on the casing, oppositely driven friction wheels having V-shaped peripheries conforming to the V-shaped recess in the driven member, suitable gearing for driving said oppositely 80 driven friction wheels, and means for shifting the movable frame.

11. In a mechanical movement, a casing, a driven member having an internal V-shaped recess, a movable frame supported 85 on the casing, oppositely driven friction wheels having V-shaped peripheries conforming to the V-shaped recess in the driven member, suitable gearing for driving said 90 oppositely driven friction wheels, and means supported on the movable frame and engaging a fixed part for shifting the movable frame.

12. A mechanical movement, comprising a casing, a driven member having an internal 95 annular friction groove, a pair of friction wheels movably mounted within said member and adapted for engagement in the friction groove thereof at the proper time, means for driving the friction wheels in opposite directions, and means for automatically 100 shifting the friction wheels alternately into engagement with the driven member.

In testimony whereof I affix my signature in presence of two witnesses as follows:
